UNITED STATES PATENT OFFICE.

CARL E. KNUTSEN, OF NEW YORK, N. Y., ASSIGNOR OF ONE-HALF TO
OLE M. KNUTSEN, OF BROOKLYN, NEW YORK.

MACHINE FOR SHAPING WROUGHT-IRON.

No. 841,326.

Specification of Letters Patent.

Patented Jan. 15, 1907.

Application filed June 4, 1906. Serial No. 320,168.

To all whom it may concern:

Be it known that I, CARL E. KNUTSEN, of the city of New York, borough of Brooklyn, county of Kings, and State of New York, have invented certain new and useful Improvements in Machines for Shaping Wrought-Iron, of which the following is a full, clear, and exact specification, reference being had to the accompanying drawings, wherein—

Figure 1 is a side elevation; Fig. 2, a front elevation of my improved anchor-iron-shaping machine; Fig. 3, a sectional view on line 3—3 indicated in Fig. 2; and Fig. 4 is an elevation of a twisting-tool that may be used in connection with my improved machine, but is not a part thereof.

My invention relates to machines for folding, bending, and otherwise shaping wrought-iron as required in the manufacture of various articles and as is ordinarily done by blacksmithing; and my invention consists particularly in devising the hereinafter-described machine for shaping anchor-irons.

The machine comprises a frame composed of uprights 4, ties 5, and braces 6, preferably riveted together, whereon the operative parts of the machine are mounted. The latter comprise an anvil or shaping-block 7, (see Fig. 3,) set up in socket 8, which is secured upon the frame by screw-bolts 9. Block 7 is provided with a semicircular groove 12, and the socket 8 is extended to either side of the anvil or shaping-block 7 to form flanges 8^a, snugly inclosing it. Flanges 8^a are slotted, their slots 11 being in line with the semicircular groove 12 of the anvil or shaping-block 7, and the lower termini of slots 11 are semicircular, being of smaller diameter than the groove 12, but concentric therewith. On the outside of the flanges 8^a brackets 14 are set, and in the upper ends thereof semicircular grooves 14^a are provided in line with the slots 11 and corresponding exactly in shape, dimensions, and position with the termini of the slots 11.

A pair of grip-jaws 17 are pivoted on bolt 16, set in flanges 8^a. These grip-jaws are two-armed levers fulcrumed on the bolt 16 to move on the outside of flanges 8^a. Their shorter arms (designated 18 in the drawings) are hook-shaped and provided with semicircular recesses 19. Their length is calculated to bring these semicircular recesses 19 exactly

opposite the semicircular termini of the slots 11 and grip and hold firmly the anchor-pin 55 32 (see Fig. 3) in its position when the grip-jaws are operated, as hereinafter more fully explained. The longer arms of the grip-jaws 17 are suitably curved and pivotally connected by links 21 and bolts 22 and 23 to 60 cross-bar 24. The latter is a double-armed lever fulcrumed on bolt 25, set in braces 6 and having its other terminus shaped into a treadle 26, by which the grip-jaws 17 are operated. On the same bolt 16, but between 65 the flanges 8^a, the hammer or movable shaping-block 27 is pivoted. This block conforms in shape to the anvil or shaping-block 7 and is provided with an arm 29, suitably long and terminating into a handle. It is 70 also provided with a semicircular groove 28, corresponding in position, shape, and dimension with the groove 12 of the block 7—that is to say, the groove 28 is in such position that when the movable shaping-block 27 75 is swung around and brought into the position shown in Fig. 3 this groove 28 comes up exactly opposite the groove 12. In this position the faces of blocks 7 and 27 are apart sufficiently to embrace and hold between the 80 two implements a bar of iron folded around a pin, as shown in the drawings.

In the operation of shaping an anchor-iron the machine is used as follows: A suitably-long piece of flat iron 31 is heated on one end 85 and then placed in the machine in the position shown in Fig. 1, the heated end resting on the anvil. An anchor-pin 32 is then laid in slots 11, (see Fig. 1,) its ends resting in the grooves 14^a of brackets 14. Then the operator 90 depresses treadle 26, bringing thereby the grip-jaws in the position shown in Fig. 3. By maintaining the pressure on the treadle 26 the bar 31 and pin 32 are held firmly in position, and the heated end of bar 31 being 95 cold the action of the grip-jaws on the pin tends to bend the end of bar 31 and to press it into the groove 12 of the anvil 7. Next the operator, while still holding treadle 26 in 100 depressed position, swings over the hammer or movable shaping-block 27 over from the position shown in Fig. 1 to that shown in Fig. 3. By this motion the end of anchor-bar 31 is coiled around the anchor-pin 32. 105 A downward pressure is then exerted on the

arm 29 of the shaping-block 27, whereby the coil of the bar 31 then lying in the grooves 12 and 28 of the blocks 7 and 27 is compressed around the anchor-pin 32, that is held firmly and exactly at right angles to the anchor-bar 31 by grip-jaws 18, acting on its ends between the flanges 8^a and the brackets 14. This operation completes the shaping of the anchor-iron, the pin and bar being thereby firmly and securely joined together. If it is required that the anchor-bar be twisted, this operation is accomplished without re-handling and while the anchor-bar is gripped in the shaping-machine by the tool shown in Fig. 4. This tool comprises a slotted head *a* and a handle *c* of suitable length. The slot *b* of this tool corresponds in dimensions with the dimensions of the flat iron used for the anchor-bar 31 to enable the operator to slide the tool upon the bar when using it. If the anchor-bar is to be twisted, the operator sets the tool thereon, the bar being embraced within the slot *b*, and while the bar is still held in the machine in the position shown in Fig. 3 then twists it by turning handle *c* of the twisting-tool down or to the right.

I claim as my invention—

1. An iron-shaping machine, comprising a frame, a grooved shaping-block and slotted flanges, one on each side of the shaping-block, set upon the frame; grip-jaws and a movable shaping-tool fulcrumed to the flanges; and means for operating the grip-jaws to close upon and to hold a pin when set

in the slots of the flanges, substantially as 35 herein shown and described.

2. An iron-shaping machine, comprising a frame, a flanged socket set upon the frame; a grooved shaping-block set in the socket, slots in the flanges in line with the groove of 40 the shaping-block; grip-jaws and a shaping-block fulcrumed to the socket, and means for operating the grip-jaws to close upon and hold a pin when set in the slots of the flanges, substantially as herein shown and described. 45

3. An iron-shaping machine, comprising a frame, a flanged socket set upon the frame; a grooved shaping-block set in the socket, slots in the flanges in line with the groove of 50 the shaping-block; grooved brackets set on 55 the flanges underneath the slots; grip-jaws and a shaping-block fulcrumed to the socket, and means for operating the grip-jaws to close upon and hold a pin when set in the slots of the flanges, substantially as herein shown and described.

4. An iron-shaping machine, comprising a frame; a grooved shaping-block and slotted flanges; one on each side of the shaping-block, set upon the frame; grip-jaws and a 60 shaping-tool fulcrumed to the flanges; a treadle, fulcrumed to the frame and a link pivoted to the treadle and to the grip-jaws, substantially as herein shown and described.

CARL E. KNUTSEN.
